Des Moines, Iowa 50316

Filed Jan. 30, 1974, Ser. No. 437,800

Term of patent 7 years

Int. Cl. D8—08

U.S. Cl. D12—115

FIG. 1 is a perspective view of a combined bicycle support and lock attaching plate showing my new design,

FIG. 2 is a side elevational view thereof,

FIG. 3 is a top plan view thereof,

FIG. 4 is a bottom plan view thereof,

FIG. 5 is a side elevational view opposite to that in FIG. 2,

FIG. 6 is a rear elevational view thereof,

FIG. 7 is a front elevational view thereof, and

FIG. 8 is a perspective view thereof to a reduced scale, it being understood that the fragmentary broken line showing of the bicycle is for illustrative purposes only.

I claim:

The ornamental design for a combined bicycle support and lock attaching plate, as shown and described.
